UNITED STATES PATENT OFFICE.

JOHN ABELL, OF TORONTO, CANADA.

CUT-OFF FOR PORTABLE OR OTHER ENGINES.

SPECIFICATION forming part of Letters Patent No. 619,110, dated February 7, 1899.

Application filed May 11, 1898. Serial No. 680,391. (No model.)

To all whom it may concern:

Be it known that I, JOHN ABELL, manufacturer, of the city of Toronto, in the county of York and Province of Ontario, Canada, have 5 invented a new and Improved Reverse and Variable Cut-Off for Portable or other Engines, of which the following is a specification.

The object of my invention is to devise a reverse and variable cut-off which will permit of the widest possible range and accuracy of cut-off, which will reverse quickly, and which is simple in construction and reliable in operation; and it consists, essentially, in operating the valve-connecting rod from a 15 crank-pin on a slide adjustable on a suitably driven crank-disk and provided with means whereby its position on the disk may be changed at will while the parts are in motion, substantially as hereinafter more specifically 20 described and then definitely claimed.

Figure 1 is a plan view of a portable engine provided with my improvements. Fig. 2 is an enlarged sectional elevation of the reverse and cut-off. Fig. 3 is a perspective view 25 of the movable sleeve. Fig. 4 is an end view of the slide and the disk on which it is movable.

In the drawings like letters of reference indicate corresponding parts in the different 30 figures.

A is the valve-chest of the engine, and B the valve-rod running in the guides in the usual manner.

C is a connecting-rod pivotally connected 35 at one end with the valve-rod and at the other journaled upon the wrist-pin D on the slide E. This slide is dovetailed to fit within a dovetailed groove formed in the face of the disk F, one side of the groove being formed 40 with an antifriction-lining, which may be removed or adjusted to take up wear. A rack G is formed upon the inner surface of the slide. The disk F is carried by a sleeve H, suitably journaled on the top of the engine. 45 A gear-wheel I is also formed on or connected to the disk F and meshes with a gear-wheel J upon the main shaft K of the engine.

Extending through the sleeve H is the shaft L, having upon the one end a pinion M, meshing 50 with the rack G. Its other end extends

out beyond the sleeve H and has a sleeve N secured thereon, which sleeve is suitably journaled, as indicated. The sleeve and shaft are preferably connected by means of a set-screw a, so that their position in regard to 55 one another can be altered.

Surrounding the sleeves H and N is a longitudinally-movable sleeve O, provided with a collar b. Surrounding this collar is a bab-bitt-lined shifter P, pivotally connected with 60 one arm of the bell-crank lever Q, suitably pivoted on the frame of the machine. The other arm of this bell-crank lever is connected by a suitable rod c with the hand-lever R, by means of which the bell-crank lever may be 65 moved as required to shift the sleeve O and to hold it as moved.

Cut in the sleeve N are the oppositely-inclined slots d, with which engage blocks, preferably pivotally connected to the sleeves H 70 and N.

From the construction described it follows that by shifting the sleeve O a rapid movement of rotation will be given to the shaft L relative to the sleeve H, and that consequently the position of the slide E upon the face of the disk F will be altered. As such a shifting of the slide moves its wrist-pin with respect to the center of the disk, it is evident that the travel of the valve-connecting rod 75 will be altered, and consequently the cut-off of the valve. The cut-off may be thus varied to admit live steam for the full length of the stroke or to permit of expansion, as may be desired, up to six-tenths of the stroke. As by 80 moving the slide the position of the wrist-pin may be instantly reversed, it is evident that the engine will be also reversed, so that the operation of the engine is entirely under control by the operator at the hand-lever R. 90

I do not wish to confine myself to the exact construction shown, as the disk F might be differently driven and different arrangements provided for shifting the relative position of the sleeve H and the shaft L while the engine 95 is in motion.

It will be seen that I have devised a very simple and effective reverse and variable cut-off, which gives to the engineer the greatest possible control over the engine and enables 100

him to secure the maximum amount of work from the engine in proportion to the fuel and water used.

What I claim as my invention is—

- 5 1. In mechanism for the purpose described a slide having a wrist-pin on one side of the center thereof on which is journaled the valve-connecting rod in combination with a disk having guides thereon in which the said slide 10 may move; a suitably-journaled sleeve on which the said disk is fast; means for revolving the said sleeve from some moving part; a shaft within the sleeve; a connection between the shaft and the slide whereby the 15 latter may be moved by the turning of the shaft; and means for turning the said shaft, substantially as and for the purpose specified.
- 20 2. In mechanism for the purpose described a slide having a wrist-pin on one side of the center thereof on which is journaled the valve-connecting rod in combination with a disk having guides thereon in which the said slide 25 may move; a suitably-journaled sleeve on which the said disk is fast; means for revolving the said sleeve from some moving part; a shaft within the sleeve; a pinion on the shaft; a rack on the slide with which the said pinion engages; and means for turning the shaft, substantially as and for the purpose specified.
- 30 3. In mechanism for the purpose described a slide having a wrist-pin on one side of the center thereof on which is journaled the valve-connecting rod in combination with a disk having guides thereon in which the said slide 35 may move; a suitably-journaled sleeve on which the said disk is fast; means for revolving the said sleeve from some moving part; a shaft within the sleeve; a connection between the shaft and the slide whereby the latter 40 may be moved by the turning of the shaft; a sleeve secured on the shaft at the end of the first-mentioned sleeve; a block projecting from each sleeve; a longitudinally-movable sleeve embracing the said sleeves and provided with oppositely-inclined slots engaging the said blocks, substantially as and for the 45 purpose specified.
- 45 4. In mechanism for the purpose described a slide having a wrist-pin thereon on which is journaled the valve-connecting rod in combination with a disk having guides thereon in which the said slide may move; a suitably-journaled sleeve on which the said disk is fast; means for revolving the said sleeve from 50 some moving part; a shaft within the sleeve; a connection between the shaft and the slide whereby the latter may be moved by the turning of the shaft; a sleeve adjustably secured on the shaft at the end of the first-mentioned 55 sleeve; a block projecting from each sleeve; a longitudinally-movable sleeve embracing the said sleeves and provided with oppositely-inclined slots engaging the said blocks, substantially as and for the purpose specified.

5. In mechanism for the purpose described 65 a slide having a wrist-pin thereon on which is journaled the valve-connecting rod in combination with a disk having guides thereon in which the said slide may move; a suitably-journaled sleeve on which the said disk is 70 fast; means for revolving the said sleeve from some moving part; a shaft within the sleeve; a connection between the shaft and the slide whereby the latter may be moved by the turning of the shaft; a sleeve secured on the shaft at the end of the first-mentioned sleeve; a block projecting from each sleeve; a longitudinally-movable sleeve embracing the said sleeves and provided with oppositely-inclined slots 75 engaging the said blocks; a collar formed on the said sleeve; a bell-crank lever adapted to engage the said collar and means for moving the said lever and holding it as moved, substantially as and for the purpose specified.

6. In mechanism for the purpose described 85 a slide having a wrist-pin thereon on which is journaled the valve-connecting rod in combination with a disk having guides thereon in which the said slide may move; a suitably-journaled sleeve on which the said disk is 90 fast; means for revolving the said sleeve from some moving part; a shaft within the sleeve; a pinion on the shaft; a rack on the slide with which the said pinion engages; means for turning the shaft; a connection between the 95 shaft and the slide whereby the latter may be moved by the turning of the shaft; a sleeve secured on the shaft at the end of the first-mentioned sleeve; a block projecting from each sleeve; a longitudinally-movable sleeve 100 embracing the said sleeves and provided with oppositely-inclined slots engaging the said blocks, substantially as and for the purpose specified.

7. In mechanism for the purpose described 105 the combination of a slide having a wrist-pin thereon on which is journaled the valve-connecting rod; a disk having guides thereon in which the said slide may move; a suitably-journaled sleeve on which the said disk is 110 fast; gearing between the said sleeve and the main shaft of the engine; a shaft within the sleeve; a connection between the shaft and the slide whereby the latter may be moved by the turning of the shaft, a sleeve secured 115 on the shaft at the end of the first-mentioned sleeve; a block projecting from each sleeve; a longitudinally-movable sleeve embracing the said sleeves and provided with oppositely-inclined slots 120 engaging the said blocks; and means for adjusting the said sleeve while the engine is in motion, substantially as and for the purpose specified.

Toronto, April 15, 1898.

JOHN ABELL.
